UNITED STATES PATENT OFFICE.

BERTRAM CHARLES JOY, OF HEMPSTEAD, LONDON, ENGLAND.

APPARATUS FOR PRODUCING A VACUUM FOR VACUUM-CLEANING AND DUST-REMOVING PURPOSES.

1,384,898.

Specification of Letters Patent. Patented July 19, 1921.

Application filed February 16, 1920. Serial No. 358,872.

To all whom it may concern:

Be it known that I, BERTRAM CHARLES JOY, formerly of 8 Dennington Park Road, West Hempstead, London, N. W. 6, and now 5 of 4 Holmdale Mansions, Holmdale Road, Hempstead, London, N. W. 6, England, have invented certain new and useful Improvements in or Relating to Apparatus for Producing a Vacuum for Vacuum-Cleaning 10 and Dust-Removing Purposes.

This invention relates to apparatus for creating a partial vacuum by means of the explosion of a combustible in a chamber and the ejection of its contents through an automatically opening outlet valve and has for 15 its object to effect dust removal and vacuum cleaning.

According to this invention automatically operating means for creating a partial vacuum comprises a single straight pistonless explosion chamber of considerable height as compared with its transverse dimensions, an inlet for air and gas or an inlet for air and an inlet for gas at or near the lower end 25 of said chamber, an outlet valve adapted to be opened by superior pressure within said chamber, at, near or connected with the upper end of said chamber and means situated above the level of said air and gas inlet or 30 inlets for igniting an explosive gaseous mixture in said chamber.

The invention is illustrated by the accompanying drawings, Figure 1 of which shows in sectional elevation one form of apparatus 35 adapted for use in conjunction with any usual form of slotted or other dust nozzle connected therewith by a flexible tube and Fig. 2 is an enlarged sectional plan on line 2-2 of Fig. 1.

An explosion chamber *a* of cylindrical form, whereof the length is considerable as compared with its diameter, is arranged, with its longitudinal axis vertical, within a water jacket constituted by a sheet metal 40 external casing *b*, and is provided with an inlet tube *c* leading from outside of the casing *b* to near the bottom of said chamber, and with an outlet tube *d* furnished with a non-return valve *e*, leading from the top of 45 the chamber to the outside of the casing *b*, where it is connected with a long exhaust pipe *d*. Near its top the chamber *a* is provided with a pipe *f* leading to the outside of the casing *b* where it is furnished with 50 a cock *g* and a nozzle *h* adapted for the at-

attachment thereto of a suction device, such as a pair of bellows for a purpose which will be hereinafter explained, while at its bottom said chamber is provided with a similar pipe *j* for draining purposes. At one side and 60 at about one quarter of the height of the chamber *a* said chamber is provided with a lateral extension in the form of a pipe *k* leading to the outside of the casing *b* and provided with a metal covering plate *m* 65 about one-sixteenth of an inch thick pierced by a small hole *n*, having a diameter of about one-sixteenth of an inch while a Bunsen burner *o* is disposed adjacent the plate *m* so that its flame plays on said plate and over 70 the hole *n*, and a sheet metal guard *p* is pivoted at *q* to the casing *b* so as, on the one hand, to inclose the flame and prevent accidental contact of clothing or the like therewith, or extinction of the flame by a current 75 of air, and, on the other hand, to enable access to be obtained to the burner *o* to light the gas. A hole *p*' is provided in the guard *p* to permit discharge of the gases escaping through the hole *n*, so that the flame of the 80 burner *o* may not be extinguished. The casing *b* which is closed by a cover *r* having a steam escape hole *s* is normally charged with water for cooling the chamber *a* and is provided with a draw-off cock *t*, from which hot 85 water may be drawn-off for domestic purposes.

The inlet pipe *c* communicates outside the casing *b* with a mixing chamber *u* into which leads an air inlet suction pipe *v* furnished with a non-return valve *w* and adapted to be connected by a flexible pipe *v*' with a suitable dust chamber, dust screen or like dust separating device and with a slotted dust nozzle or the like of usual construction, which is adapted to be moved over and in contact with the carpet or other fabric to be cleaned. If desired the dust separating device may be secured to the casing *b*, or otherwise suitably, and interposed between the flexible pipe *v*' and the air inlet suction pipe *v*. In open communication with the mixing chamber *u*, and consequently with the combustion chamber *a*, through a circular series of ports *x* and a screen *y* composed of one or more sheets of wire gauze or the like, is a pipe *z*, coiled upon itself adjacent the casing *b* and connected through a flexible pressure regulating bag 11 with a coal gas supply pipe 12, 110

furnished with a cock 13, while the pipe *z* is furnished with an adjusting screw valve 14.

Assuming the apparatus to be full of air, 5 the gas issuing from the Bunsen burner *o* to be ignited and the gas supply to be turned on at the cock 13, and assuming a suction device, such as a pair of bellows, the form of which is so well known as not to require 10 description to be attached to the nozzle *h*, and the cock *g* to be open, the withdrawal of air from the chamber *a* through the pipe *f* draws in gas through the pipe *z*, the mixing chamber *u* and the inlet pipe *e*. The 15 gas thus drawn in mixes with the air at the bottom of the combustion chamber *a* and a tongue of flame is drawn in through the aperture *n*. As soon as or about the time, the level of the gaseous mixture reaches the 20 level of the aperture *n*, said mixture explodes and the greater part of the contents of the chamber are expelled through the outlet pipe *d*, the valve *e* automatically opening. At the same time a portion of the products 25 of combustion is driven back through the inlet pipe *e*, mixing chamber *u*, ports *x*, and screen *y*, into the pipe *z* (but not so far as the bag 11)—and drives back the gas in said pipe. The remainder of the air and products 30 of combustion left in the chamber *a* are rapidly cooled by the surrounding walls and on contraction create a partial vacuum, close the valve *e* and draw in air through the air inlet suction pipe *v* (the valve *w* opening 35 automatically), and products of combustion through the pipe *z*. The air and products of combustion thus drawn in rise in the chamber *a* as a separate stratum and do not mix with the air and products of combustion already therein and are followed, when the products of combustion in the pipe *z* have been withdrawn therefrom, by a gaseous mixture resulting from the simultaneous entrance to the mixing chamber *u* 40 and from opposite sides thereof, of gas through the pipe *z* and air through the pipe *v*.

The admission of gas to the combustion chamber *a* is thus delayed until after a portion 50 of the air has been drawn into said chamber thus effecting an economy of gas as the gaseous mixture follows the air and products of combustion as a more or less separate stratum and does not mix therewith to any appreciable extent. Further the delayed admission of coal gas effectually prevents pre-ignition of the entering gas by burning products of the previous explosion which may be lingering at the bottom of the chamber *a*, in the inlet pipe *e*, or in the mixing chamber *u*. During the whole of the suction period a tongue of flame is drawn in through the aperture *n* but without producing any explosion until the level 55 of the gaseous mixture reaches that of said

aperture, when an explosion takes place automatically closing the inlet valve *w*, opening the outlet valve *e* and initiating another cycle of operations as described above, and so on, so long as gas is supplied from the 70 pipe 12, thus maintaining a partial vacuum in the flexible pipe *v'*.

It is desirable that the lift of the inlet valve *w* should be limited so as to slightly restrict the flow of air therethrough in order 75 to prevent air entering the explosion chamber *a* so rapidly as, on the one hand, to upset, or tend to upset, stratification of the contents of the chamber, and, on the other hand, to interfere with the drawing in of the flame 80 through the hole *n*, both of which would cause unreliable working.

The provision of a long exhaust pipe *d'* is desirable, though not essential, as the inertia of the gases flowing therethrough tends 85 to increase the degree of vacuum attained in the apparatus and if desired the exhaust valve *e* may be placed at the outlet end of the exhaust pipe *d'*. Further, air and gas inlets may be arranged to enter the chamber 90 *a* from opposite sides thereof, the end of the explosion chamber constituting a mixing chamber, and the valves *e* and *w* may, if desired, be furnished with springs.

In some cases electric or other means of 95 ignition may be provided, but it has been found that the "touch-hole" means hereinabove described are eminently suitable, being very simple and not likely to fail, while the loss of vacuum pressure due to the aperture 100 *n* is negligible.

The apparatus may be disposed in any convenient part of a building and connected with any other part by means of a long flexible pipe as is usual with vacuum cleaning apparatus of more or less stationary type, or fixed pipe connections may be provided, such fixed pipes being furnished at suitable points with means for coupling thereto a flexible pipe and usual dust nozzle. 110

I claim:—

1. For vacuum cleaning apparatus, automatically operating means for creating a partial vacuum, comprising a pistonless explosion chamber of considerable length as 115 compared with its transverse dimensions, an inlet for air and gas near one end of said chamber, a mixing chamber communicating with said inlet, a screen of reticulated material adjacent said mixing chamber, a gas 120 supply pipe in open communication with said explosion chamber through said screen and said mixing chamber and inlet, an air inlet suction pipe opening into said mixing chamber adjacent said gas supply pipe, a 125 non-return valve in said air inlet pipe, an outlet valve connected with the other end of said chamber and adapted to be opened by superior pressure within said chamber, and means for igniting an explosive gaseous 130

5 mixture in said chamber, the arrangement being such that when an explosion takes place in the explosion chamber, the gas supply is driven back in the gas supply pipe and replaced by products of combustion, so that the latter must be withdrawn from the gas supply pipe at the same time that air is drawn in through the air inlet suction pipe, before gas and air can be drawn in 10 simultaneously.

15 2. For vacuum cleaning apparatus, automatically operating means for creating a partial vacuum, comprising a pistonless explosion chamber of considerable length as compared with its transverse dimensions, an inlet for air and gas near one end of said chamber, a mixing chamber communicating with said inlet, a screen of reticulated material adjacent said mixing chamber, a gas 20 supply pipe in open communication with said explosion chamber through said screen and said mixing chamber and inlet, an air inlet suction pipe opening into said mixing chamber adjacent said gas supply pipe, a non-return valve in said air inlet pipe, an 25 outlet valve connected with the other end of said chamber and adapted to be opened by superior pressure within said chamber, and means for igniting an explosive gaseous 30 mixture in said chamber, said means being situated between the inlet for gas and air and the outlet valve, the arrangement being such that when an explosion takes place in the explosion chamber, the gas supply is 35 driven back in the gas supply pipe and replaced by products of combustion, so that the latter must be withdrawn from the gas supply pipe at the same time that air is drawn in through the air inlet suction pipe, before gas and air can be drawn in simultaneously.

40 3. For vacuum cleaning apparatus, automatically operating means for creating a partial vacuum, comprising a pistonless explosion chamber of considerable length as compared with its transverse dimensions, an inlet for air and gas near one end of said chamber, an outlet valve connected with the other end of said chamber and adapted to be opened by superior pressure within said chamber, and means for igniting an explosive gaseous mixture in said chamber, said means comprising a gas burner, a plate 45

50 on the wall of the explosion chamber, said plate being provided with a small aperture in constant communication with the interior of said explosion chamber, the flame issuing from said burner being directed toward and normally playing against said apertured plate, a tongue of flame being sucked 55 into said explosion chamber without the employment of any valve when a partial vacuum is created in said chamber.

55 4. For vacuum cleaning apparatus, automatically operating means for creating a partial vacuum, comprising a pistonless explosion chamber of considerable length as compared with its transverse dimensions, an inlet for air and gas near one end of said chamber, a mixing chamber communicating with said inlet, a screen of reticulated material adjacent said mixing chamber, a gas supply pipe in open communication with said explosion chamber through said screen and said mixing chamber and inlet, an air 60 inlet suction pipe opening into said mixing chamber adjacent said gas supply pipe, a non-return valve in said air inlet pipe, an outlet valve connected with the other end of said chamber and adapted to be opened by 65 superior pressure within said chamber, and means for igniting an explosive gaseous mixture in said chamber, said means being situated between the inlet for gas and air and the outlet valve and comprising a gas 70 burner, a plate on the wall of the explosion chamber, said plate being provided with small aperture in constant communication with the interior of said explosion chamber, the flame issuing from said burner being 75 directed toward and normally playing against said apertured plate, a tongue of flame being sucked into said explosion chamber without the employment of any valve 80 when a partial vacuum is created in said chamber, the arrangement being such that when an explosion takes place in the explosion chamber, the gas supply is 85 driven back in the gas supply pipe and replaced by products of combustion, so that the latter must be withdrawn from the gas supply pipe at the same time that air is drawn in through the air inlet suction pipe, before gas and air can be drawn in simultaneously.

90 95 100 BERTRAM CHARLES JOY.
